John H. Morgan,
ATTORNEY.

UNITED STATES PATENT OFFICE

GEORGE L. HAMMON, OF SAN FRANCISCO, CALIFORNIA, ASSIGNOR TO NATIONAL WELDING EQUIPMENT COMPANY, INCORPORATED, OF SAN FRANCISCO, CALIFORNIA

HEATING TORCH

Application filed November 5, 1930. Serial No. 493,542.

This invention relates to improvements in heating torches, or blowpipes, and more particularly to the control of the heating flame in the type of torch in which gas and compressed air are used, and it also relates specifically to torches for using natural gas.

One object of my invention is to provide a heating torch in which natural gas and compressed air can be used in the most efficient way.

Another object is to produce a torch in which the heating flame can be regulated by the hand in which it is held, so that a light or brush flame can be changed instantly to a concentrated flame of intense heat.

Another object is construction of the nozzle having multiple concentric heating and igniting flames to provide a wide variation of flames without blowing out.

Another object is to provide a gas and air mixer in the regulator body, and tubular connections to the nozzle.

Another object is the use of a central tube connected to the mixer and terminating in a chamber in the nozzle, said chamber being connected to all the concentric chambers.

Another object is the provision of an intermediate support for the central tube without unduly obstructing the passage of gas in the outer tube.

Other objects will appear to those skilled in the construction of torches of this type, as the description progresses.

An embodiment of the invention is shown in the accompanying drawing in which the same reference numeral is applied to the same portion throughout the several views, and of which there may be modifications:

Fig. 1 is a side elevation of the complete torch, broken away in part.

Fig. 2 is a plan view of the complete torch.

Fig. 3 is an enlarged view partly in section of the torch.

Fig. 4 is an enlarged section taken on line 4-4 of Fig. 3.

Fig. 5 is an enlarged sectional view of the fuel mixer, detached.

Fig. 6 is an end view of tip end of Fig. 3 showing concentric chambers and openings.

Fig. 7 is perspective of the end portion of the central tube in a modified form.

The numeral 1 indicates the regulator body which has the gas connection 2 and the air connection 3 to which the terminals 4 and 5 having flexible tubes (not shown) are attached. The compressed air port 6 leads to a port 7 at right angles to port 6 and that port is connected to the chamber 8.

A needle valve 9 closes the passage way 60 between ports 6 and 7 and it has the threaded stem 10 on which is fixed the knurled wheel 11 to control the needle valve.

The gas port 12 leads to a port 13 controlled by the needle valve 14 which has the threaded stem 15, on which is fixed the knurled control wheel 16.

The port 13 leads to the annular channel 17 in the mixer body 18.

The mixer has the central opening 19, and 70 small holes 20, leading from the channel 17 to the chamber 8.

Connected to the mixer is the outer extention tube 22, by means of the threads 23 and a central tube 24 is connected to the mixer by 75 the threads 25.

The mixer and extention tubes are held in place by the threaded coupling nut 26.

The tubes 22 and 24 are of suitable length and may be curved to suit the work being 80 done, in the present instance straight tubes are shown, on which is mounted the nozzle 27.

The nozzle is connected to the tube 22 by means of the bushing 28 which is threaded on 85 at 29. External threads 30 on the bushing engage threads on the nozzle 27. The bushing has the radial slots 32 which communicate with enlargement of chamber 34, which carries the mixed gas and air from the mixer. 90

The central tube 24 has the tip fixed therein which has the reduced opening 35, the end of the tube projects into the chamber 36 and is spaced from the end of the central tube 37 of the nozzle and in alignment therewith. 95

In the nozzle 27 is mounted the concentric ring 38 forming the concentric chamber 39 around the central tube, and the concentric ring 40 forming the concentric chambers 41 and 42. 100

Chamber 39 has the holes 43 to the chamber 36.

Chamber 41 has the holes 44 to the chamber 36 and chamber 42 has the holes 45 to the chamber 36, chamber 36 gets gas mixture from chamber 34 through plurality of slots 32.

A spiral spring 47 acts as a support for the central tube 24, to hold it central and allow a free flow of the gas mixture.

In the regulator, the valve 48 closes the opening 19 to the chamber 8, and this valve has the stem 49 extending outside of the body, a spring 50 acts to hold the valve seated, suitable packing 51 is provided for the stem. On the outside of the body is the bell-crank thumb lever 52 pivoted at 53 and it has the vertical depending members 54 and 55, one on each side of the valve stem. These members act against the adjustable collar 56, to move the valve off its seat. A lock-nut 57 holds the collar in adjustment.

In the operation of the heater, connection having been made with a source of supply of gas and compressed air, the needle valve 14 is adjusted to admit gas to the mixing channel 17 where it whirls around and is cut through at right angle, by air jets from the openings 20, chamber 8, and port 7 controlled by the needle valve 9. As the gas and air are mixed the mixture passes through the holes 58 to the annular chamber 34, from there through the slots 32 to the chamber 36, to central tube 37, through holes 43 to concentric chamber 39, through holes 44 to concentric chamber 41 and through holes 45 to concentric chamber 42. At this stage, the central flame, and all of the concentric flames are burning which results in a long brush like flame for moderate heating.

Now, when the lever 52 is pressed, it acts to pull back the valve 48 and allow a considerable amount of compressed air to blow through the central tube, which acts to insiprate more gas from chamber 36 through the central orifice of the tip thus restricting the amount of the mixture passing through the outer chambers and thus cutting down the concentric flames surrounding the central tube at the nozzle, with the result that a shorter and intensely hot flame is produced which can be further regulated by the needle valves.

The action of the mixture passing across the space between the end of tip 35 and the tube 37 is to draw the mixture from the concentric chambers and thus further concentrate the central flame.

As soon as the lever is released the spring 50 closes the valve 48 and the brush flame re-60 turns.

The needle valves, and the lever are operated by the fingers of the hand that holds the torch.

Having thus described my invention what I desire to protect by Letters Patent of the

United States is as follows, but modification may be had in carrying out the invention as shown in the accompanying drawing and particularly described form thereof within the purview of the annexed claims.

I claim:

1. A heating torch comprising a torch body, means to mix air and gas in said body, a flame nozzle for said torch, means to distribute a certain amount of said mixture to said nozzle to produce a moderate heating flame, means to regulate said distributing means, an auxiliary means for admitting additional air to produce an intense heating flame, and automatically reduce said moderate heating flame.

2. A heating torch comprising a regulating body, a flame nozzle connected to said body, a gas and air mixer in said regulating body, a central passage from said mixer to said nozzle, a passage concentric to the central passage from the mixer to the nozzle, a plurality of concentric chambers in said nozzle, means to control the gas mixture in said passages to produce a central flame and a plurality of flames concentric to said central flame, and means to concentrate the flames to a central flame of intense heat, by the admission of compressed air to the central passage.

3. A heating torch comprising a regulator body, means to supply gas and compressed air to said body, a mixer for said gas and air in said body, a flame nozzle, means to connect the nozzle to said mixer, means to control the flow of gas and air separately to said mixer, and auxiliary means to allow compressed air to flow to the central portion of said nozzle.

4. A heating torch of the class described comprising a regulator body, means to connect said body to sources of fuel gas and compressed air, a mixing chamber, passageways leading from said connections to the mixing chamber, valves to open or close said passageways, a chamber to receive air from the air passage adjacent said mixing means, a flame nozzle having a central passage way to said chamber, a valve to open or close the connection between the chamber and the central passageway, means to operate said valve from the outside of said regulator body, and a passageway from said mixing chamber to said nozzle.

5. A heating torch of the class described comprising a regulator body, a detachable air and gas mixer in said body, a conical face on said mixer, a seat in said body for said face, a tube attached to said mixer, a coupling to secure said tube and mixer in the body, a smaller tube mounted inside said tube and connected to the mixer, a nozzle mounted on the outer end of said tube, a chamber in said nozzle, into which the end of said smaller tube projects, ports adapted to conduct air and gas to said mixer, valves for controlling said ports, an air chamber communicating

with said mixer, an opening from said chamber to the smaller tube, a valve adapted to close said opening, and means to operate said valve from the outside of said body.

5 6. A heating torch nozzle comprising a plurality of concentric chambers, open at the outer ends, and closed by a wall spaced from the rear end thereof, spaced openings through said wall in said chambers, a bushing spaced from said wall in the rear of said nozzle, spaced slots in the inner end of said bushing communicating with a fuel mixture chamber a central tube connecting with said mixture chamber, means to blow fuel mixture through said chamber and thus through the concentric chambers, and means to blow a fuel mixture through the central tube.

10 7. A heating torch having a regulator body, compressed air and gas connections on said body, a nozzle, a mixer in said nozzle, a gas and air mixer in said body, a central opening through the mixer to the nozzle mixer, a passageway from the mixer to the nozzle mixer, an air chamber communicating with the central opening in said body, a valve to open or close said opening, a port leading from the air connection to said chamber, a valve in said port, a port leading from the gas connection to the mixer, a valve in said 15 opening through the mixer to the nozzle mixer, to the air chamber, and means to operate all of said valves from the outside of the regulator body.

20 8. A torch of the class described comprising a regulator body, an air chamber in said body, a valve controlled port leading to said chamber, a mixer member adapted to close one end of said chamber, small openings into the mixer from the chamber, a central opening through the mixer, a valve adapted to close said opening into the chamber, a stem fixed to said valve, and extending outside of said body, collars on the free end of said stem, a spring adapted to hold the valve closed, a 25 bell crank thumb lever pivoted on the outside of said body and having forked members adapted to engage the collar on said stem whereby the pressing down of the thumb lever will move the valve and open the central opening to the chamber, a nozzle having a central opening in alignment with said central opening and a plurality of concentric chambers in said nozzle connected to the mixer.

30 9. A torch of the class described comprising a regulator body having gas and compressed air connections and ports, valves to control said gas and air, an extension tube, a mixer mounted on said tube, means to attach said mixer and tube to said body, a nozzle mounted on the other end of said tube, a mixing chamber in said nozzle a central opening through said mixer in said body, a small tube in said opening extending to the mixing chamber in said nozzle, a nipple in the

end of said small tube having a reduced opening, a central tube in the nozzle communicating with the mixing chamber and in alignment with the opening in said nipple, but spaced therefrom, and a valve adapted to admit air to the central opening.

35 10. A heating torch of the class described comprising a regulator body having gas and compressed air connections and ports, a compressed air chamber, a valve to control the supply of air thereto, a central tube leading from said chamber, a valve to close the outlet of said tube from the chamber, means to operate said outlet valve from the outside of said regulator body, a fuel mixture chamber, a valve to control the supply of fuel to said chamber, small openings connecting said fuel chamber with said compressed air chamber, an outside tube forming a passageway around the central tube and leading from said fuel mixture chamber, a nozzle on said outside tube, a fuel mixture chamber in said nozzle, a series of concentric chambers having openings to said mixture chamber, a short tube connected to the mixture chamber in alignment with said central tube, but spaced from the end thereof, means to supply the concentric chambers and short tube with fuel mixture to produce a moderate heating flame, and means to admit compressed air through the central tube and across the space at its end through the short tube to produce an intensified heating flame by drawing to the center the fuel mixture that supplies the concentric flames.
